Patented Oct. 24, 1916.

UNITED STATES PATENT OFFICE.

HENRY S. MOODY, OF DALLAS, GEORGIA.

PLOW.

1,202,563.

Specification of Letters Patent. Patented Oct. 24, 1916.

Application filed September 22, 1915. Serial No. 51,956.

To all whom it may concern:

Be it known that I, HENRY S. MOODY, a citizen of the United States, residing at Dallas, in the county of Paulding and State of Georgia, have invented certain new and useful Improvements in Plows, of which the following is a specification.

This invention relates to plows and contemplates more particularly, an improved mechanism whereby a plow point or shovel may be readily and quickly attached to or detached from the plow.

The invention has as a further object to provide a clamping means for the plow point adapted to hold said point against lateral as well as vertical shifting movement and to also provide a construction wherein, if desired, a weeder may be attached to the plow simultaneously with the attachment of the plow point thereto. And a still further object of the invention is to provide an improved construction of this character employing a single clamping lever for holding the plow point upon the plow and which will be easily accessible so that the plow point may be detached without difficulty.

Other and incidental objects will appear as the description proceeds and in the drawings wherein I have illustrated the preferred embodiment of the invention and wherein similar reference characters designate corresponding parts throughout the several views, Figure 1 is a perspective view of my improved plow with the plow point attached thereto, and Fig. 2 is a vertical sectional view more particularly showing the construction and mounting of the clamping means for the plow point.

In carrying out my invention, I employ a stock which preferably includes spaced side members 10 to the upper extremities of which is suitably connected a beam 11. The stock 10 is preferably curved longitudinally and connecting the side portions thereof intermediate the ends of the stock is a web or block 12. Adjacent the lower extremity of the stock, the forward edges of the side members thereof are each provided with a series of longitudinally spaced and oppositely disposed notches or stops 13. Mounted upon the rear face of the stock to extend longitudinally thereof is a clamping member 14 which also, as will presently appear, provides a blade receiving member. This member is preferably formed from a strip of suitable resilient sheet metal and is pro-

vided adjacent its extremities with longitudinally extending slots 15 and 16 respectively. Extending through the slot 15 of the clamping member and adjustably connecting the said member with the stock is a set screw or other suitable fastening device 17 screw threaded into the block 12. Normally, the clamping member 14 is straight and adjacent the lower end thereof, is provided with an upstanding lug 18, substantially rectangular in cross-section and adapted to fit between the side members of the stock.

Mounted upon the forward edges of the side members of the stock adjacent the lower end thereof is a clamping element or blade-engaging member provided upon its inner face with a laterally projecting lug 20 also substantially rectangular in cross-section, the lug 20 being arranged adjacent the lower end of the clamping member. Extending laterally from the upper end of the clamping member in the direction of the lug 20 is an arm 21 which is freely received between the side members of the stock and projects through the slot 16 of the clamping member 14. Mounted upon the outer end of the arm 21, is a locking lever 22, the lower end of which is bifurcated to receive the said arm and is formed into a cam 23 through which extends a suitable pivot pin connecting the lever with the arm.

In the drawings, I have shown a conventional type of plow point or shovel 24 mounted upon the lower end of the stock and seating against the forward edges of the side members thereof with the upper end of the plow point engaging corresponding notches of the series of notches 13. The plow point will thus be supported against vertical shifting movement upon the stock. To so connect the plow point with the stock, the lever 22 is first swung upon its pivot away from the stock when the lower extremity of the yieldable clamping member 14 will spring away from the lower end of the stock. The clamping member 19 may then be easily shifted so that the plow point may be inserted between the said clamping member and the stock. Preferably, the plow point is provided with a longitudinally extending slot 25, at its upper extremity, which receives the lug 20 of the clamping member 19 so that when the locking lever 22 is moved to its normal position, as illustrated in the drawings, the plow point will

not only be held against vertical shifting movement upon the stock, as above pointed out, but will also be held against lateral shifting movement thereon through the medium of the lug 20, the lever 22 being adapted to clamp the member 19 tightly against the plow point to hold it fixed upon the stock. In this connection, it may be pointed out that the upper end of the clamping member 19 may also be engaged in corresponding notches of the series of notches 18 so that the said clamping member will be held against vertical shifting movement upon the stock. If desired, a weeder 26 may also be employed in connection with the present construction. This weeder is preferably formed from a single piece of material bent to provide blades extending laterally upon opposite sides of the stock with the intermediate portion thereof fitting within suitable notches formed in the rear edges of the side member of the stock as more particularly shown in Fig. 2 of the drawings. The intermediate portion of the weeder is provided with an opening which receives the lug 18 of the clamping member 14 so that the said weeder will be firmly held in position upon the stock both as against vertical and lateral shifting movement.

It will now be clear that the plowshare may be adjusted vertically of the stock as may also the coacting clamping members 14 and 19. The presence of the yieldable clamping member 14 will eliminate any rattling between the parts, and by properly manipulating the lever 22 which, as will be observed, is in a position where it will be readily accessible, the plowshare or the weeder may be easily attached to or detached from the stock. In this connection, it is pointed out that the member 14 will yieldably engage the locking lever 22 for holding it at adjustment with the clamping members in their normal operative position.

Having thus described my invention, what I claim and desire to secure by Letters Patent is:

1. A device of the character described including a stock, a blade engaging member arranged to coact with the stock for supporting a blade, locking means for the said member, and yieldable means associated with the said locking means for holding the said locking means in active position with the said yieldable means providing a blade engaging member coacting with the stock for receiving a blade therebetween. 50

2. A device of the character described including a stock, blade engaging members carried thereby, and locking means associated with the said members and movable for shifting the said members toward the stock for clamping a blade between each of the said members and the stock. 60

3. A device of the character described including a stock, coacting blade engaging members adjustable upon the stock, and locking means associated with said members for shifting the said members toward the stock for clamping a blade between each of the said members and the stock. 65

4. A device of the character described including a stock, a blade engaging member carried thereby, a locking lever associated with said member and adjustable for shifting the member toward the stock to active position, and a resilient blade engaging member yieldably bearing against the lever for holding it at adjustment. 75

5. A device of the character described including a stock having a notch formed in the rear side thereof, a blade engaging member cooperating with the forward side of the stock, a second blade engaging member co-operating with the rear side of the stock, and means adjustable for shifting the said members toward the stock to each engage a blade seated against the stock with one of the said blades received in said notch and with the said second mentioned member providing a yieldable element for holding the said means at adjustment. 80 85 90

In testimony whereof I affix my signature.
HENRY S. MOODY. [L. S.]
